TO SANFORD RILEY STOKER CO., OF WORCESTER, MASSACHUSETTS, A CORPORA-
TION OF MASSACHUSETTS.

FURNACE-FEEDING MECHANISM.

Application filed December 31, 1921. Serial No. 526,325.

This invention relates to the fuel feeding mechanism of an underfeed stoker and particularly to improved mechanism by which the rate of fuel feed in each separate stoker 5 retort may be varied as desired.

It has been found extremely desirable to be able to vary the rate of feed to suit different conditions of load as well as variations in the nature of the fuel and in the 10 condition of the fuel bed. It is customary, however, to drive the fuel feeding plungers or rams from a crankshaft which commonly moves at a single continuous rate of speed.

It is one object of our invention to provide 15 means for positively advancing each fuel feeding plunger to a definite inmost position on each feeding stroke and for varying the position to which the plunger is withdrawn on its idle or inoperative stroke. With this 20 general object in view, an important feature of our invention relates to the provision of a two-piece plunger, together with the provision of mechanism permitting a desired amount of lost motion between the two 25 parts of the plunger.

Another feature of our invention relates 30 to the provision of novel adjusting devices by which the amount of lost motion for each plunger in a multiple retort furnace may be separately adjusted, and by which also all 35 of the plungers may be simultaneously reset.

Our invention further relates to arrangements and combinations of parts which will be hereinafter described and more particularly pointed out in the appended claims.

A preferred form of our invention is shown in the drawing in which—

Fig. 1 is a sectional elevation of portions 40 of a stoker retort and fuel feeding mechanism embodying our improvements,

Fig. 2 is a perspective view of two of the 45 adjusting bars,

Fig. 3 is a partial side elevation of one of the adjusting bars and its operating wheel,

Fig. 4 is a diagrammatic fragmentary 50 plan view of a plurality of retorts and fuel feeding mechanism associated therewith.

Referring to the drawings, we have shown 55 portions of an underfeed furnace of a usual form, including a hopper 10, a cylinder 11, a fuel chute or passage 12 leading to the retort and a crankshaft 13 continuously rotated from any suitable source of power

(not shown). In the operation of the stoker, 55 the hopper 10 is supplied with coal or other fuel which is forced through the passage 12 to the retort by the action of a fuel feeding plunger driven by the crankshaft 13. Our improvements relate particularly 60 to the construction and operation of this plunger.

As shown herein, our improved plunger comprises a plunger head 14, and an open cylinder or sleeve 15. A connecting rod or link 16 is pivoted at one end on the crankpin 17 of the crankshaft 13, and at its other and forked end it is pivoted at 18 in the sleeve 15. The plunger head 14 is provided with a series of inwardly projecting flanges 70 or ledges 19 which are positioned for engagement by the hook-shaped end of a lever 20 pivoted at 21 on the sleeve 15. The lever 20 has an upwardly extending end 22 which normally engages the outer edge of the 75 sleeve 15 and is positioned thereby as shown in Fig. 1. A weight 20^a on the lever 20 holds the hook-shaped end of the lever yieldingly depressed.

A separate adjusting bar 23 is provided 80 for each retort and plunger. Each bar 23 has a series of saw-tooth projections 24 on its lower face, and these teeth mesh with corresponding teeth on cog wheels 25 fixed to a shaft 26 which preferably extends 85 across the entire series of retorts.

At its front or right-hand end (as viewed in Fig. 1) each bar 23 has a pair of projections or lugs 27 which are disposed in grooves or recesses 28 formed by horizontal 90 guide-bars 29 secured to the top of the cylinder 11 and on each side of a longitudinal slot 30 through which the part 22 of the lever 20 travels. Each bar 23 is also provided with a lug 31 at its opposite end resting upon the 95 top of one of the guide-bars 29 and preventing undue depression of the rear end of the adjusting bar. It will be also noted in the drawings that the teeth 24 at each of the curved ends of the bar 23 are decreased in 100 depth as clearly shown in Fig. 3 for a purpose to be described.

Having described the details of construction of our improved mechanism, the method 105 of operation thereof is as follows:

When a fire is started it is usually desirable to operate each feeding mechanism at its full capacity and for this purpose the ad-

justing bars 23 are all placed in the position shown in Fig. 1. The hooks of the levers 20 thus remain in engaging position and the plunger head 14 receives substantially the 5 full stroke of the sleeve 15 in both directions.

The travel of the sleeve 15 is directly effected by the crank-shaft 13, and the sleeve is thus regularly reciprocated over a path of fixed and definite length.

- 10 When it is desired to reduce the rate of fuel feed in a particular retort, the corresponding adjusting bar 23 is moved forward by raising the rear end of the bar so that the teeth 24 are disengaged from the cog wheel. 15 The bar is then advanced to a selected position, as indicated in Fig. 2, and the outer or front end of the bar engages the lever projection 22 as the sleeve and plunger head move forward and raises the hook-shaped 20 end of the lever out of operative position.

As the sleeve is withdrawn on its idle stroke, the lever hook passes over the flanges or ledges 19 until the sleeve reaches a point where the projection 22 is freed from its bar 23, permitting the hook to descend and engage one of the flanges 19. By suitably adjusting the bar 23, the hook may be caused to engage any desired flange 19, thus providing any desired amount of lost motion between 25 the sleeve and the plunger head and correspondingly reducing the outward travel of the plunger head. Each separate plunger may thus be independently adjusted to suit the working conditions in a particular retort. 30

It is sometimes desirable, however, to reset all of the adjusting bars to provide full working strokes for each plunger, and for this purpose the shaft 26 may be manually 40 rotated to return all of the adjusting bars to the position shown in Fig. 1. If the bars have been heretofore differently adjusted, as indicated in Fig. 2, it is evident that some of the bars will reach the desired position in 45 advance of other bars, and for this purpose the reduced teeth at the end of the bars are provided so that the cog wheels may slip idly past the partial teeth of the bars when the latter have reached their inmost position. 50

Our invention has been herein described as particularly adapted to a multiple retort stoker, but it should be understood that the invention also serves many useful purposes 55 when used in a single retort stoker. This is particularly the case when a number of single stokers have a common air supply or common actuating mechanism.

Having thus described our invention, it 60 will be seen that we have provided a very simple mechanism by which the rate of fuel feed in a stoker retort may be controlled as desired, or, in fact, may be entirely discontinued without interfering in any way with 65 the operation of other retorts. It will be

further evident that changes and modifications may be made in our invention by those skilled in the art within the spirit and scope thereof as set forth in the claims, and we do not wish to be otherwise limited to the details herein disclosed but what we claim is:—

1. In an underfeed stoker, a plurality of coal-engaging and coal-feeding members, driving mechanism therefor, separate connections between said driving mechanism 70 and the coal-feeding members, separately adjustable devices effective to shorten the feeding strokes of selected coal-feeding members, and means to simultaneously set all of said adjustable devices for full stroke 75 operation of said feeding members.

2. In an underfeed stoker, a cylinder, a fuel feeding plunger slidable therein, said plunger comprising a sliding member and a plunger head, one of said elements having a series of abutments therein, a latch mounted on the other of said elements and adapted to engage a selected abutment, and means effective to separate said latch from its abutment at a selected point in the idle 80 return stroke of said plunger, said sliding member having operative driving engagement with said plunger head on the working stroke of said plunger.

3. In an underfeed stoker, a plurality of coal-engaging and coal-feeding members, driving mechanism therefor, a separate connection between said driving mechanism and each coal-feeding member, separately adjustable bars and means on said members co-operating with said bars effective to vary the feeding strokes of selected coal-feeding members, and means to simultaneously set 100 all of said bars in position for full stroke operation of said feeding members.

4. In an underfeed stoker, a cylinder, a fuel feeding plunger slidable therein, said plunger comprising a sliding member and a plunger head, said head having a series of projections thereon, a hook mounted on said member, and means to cause said hook to engage a selected projection on the idle return stroke of said member, said member having operative driving engagement with said head on the working stroke of said plunger. 110

5. In an underfeed stoker, a cylinder, a fuel feeding plunger slidable therein, said plunger comprising a sliding member and a plunger head having a series of internal flanges, a hook lever mounted on said member, and means to move said lever to form operative engagement with a selected one of said flanges, said member having operative driving engagement with said head on the working stroke of said plunger. 120

6. In an underfeed stoker, a cylinder, a fuel feeding plunger slidable therein, said plunger comprising a sliding member and a plunger head having a series of internal flanges, a hook lever mounted on said mem- 130

ber, and means to move said lever to form operative engagement with a selected one of said flanges, said means comprising an adjusting bar movable to different positions 5 in the path of travel of said lever, and said member having operative driving engagement with said head on the working stroke of said plunger.

7. In an underfeed stoker, a cylinder, a 10 fuel feeding plunger slidable therein, said plunger comprising a sliding member and a plunger head having a series of internal flanges, a hook lever mounted on said member, and means to move said lever to form 15 operative engagement with a selected one of said flanges, said means comprising an adjusting bar having a toothed lower surface and a cog wheel engaged thereby, said wheel being normally at rest to hold said 20 bar in adjusted position, and said member having operative driving engagement with said head on the working stroke of said plunger.

8. In an underfeed stoker, a cylinder, a 25 fuel feeding plunger slidable therein, said plunger comprising a sliding member and a plunger head having a series of internal flanges, a hook lever mounted on said member, and means to move said lever to form 30 operative engagement with a selected one of said flanges, said means comprising a toothed adjusting bar, a cog wheel engaged

thereby, and means to rotate said wheel to reset said bar, said member having operative driving engagement with said head on 35 the working stroke of said plunger.

9. In an underfeed stoker, a cylinder, a fuel feeding plunger slidable therein, said plunger comprising a sliding member and a plunger head having a series of internal 40 flanges, a hook lever mounted on said member, and means to move said lever to form operative engagement with a selected one of said flanges, said means comprising a cog wheel, a toothed adjusting bar normally 45 engaging said wheel but adapted to be raised out of engagement therewith, and means to rotate said wheel, said member having operative driving engagement with said head on the working stroke of said 50 plunger.

10. In an underfeed stoker, a plurality of coal feeding mechanisms, toothed adjusting bars for said mechanisms, a shaft, cog wheels on said shaft engaged by said bars, and 55 means to rotate said shaft, the teeth at the ends of said bars being of reduced depth to permit slipping of said cog wheels when the bars reach their limits of travel.

In testimony whereof we have hereunto 60 affixed our signatures.
